US00D639627S

(12) **United States Design Patent**
Seeds et al.

(10) **Patent No.:** US D639,627 S
(45) **Date of Patent:** ** Jun. 14, 2011

(54) **COMMUNICATION TOOL**

(75) Inventors: **Darrin Seeds**, Vancouver, WA (US);
John Nason, Keizer, OR (US); **Hal Hardinge**, Tigard, OR (US)

(73) Assignee: **Fiskars Brands, Inc.**, Madison, WI (US)

(**) Term: **14 Years**

(21) Appl. No.: **29/362,612**

(22) Filed: **May 27, 2010**

(51) **LOC (9) Cl.** **08-05**

(52) **U.S. Cl.** **D8/52**

(57) **CLAIM**

We claim the ornamental design for a communication tool, as shown and described.

DESCRIPTION

FIG. 1 is a perspective view of a handle of the claimed design.

FIG. 2 is a right side view thereof.

FIG. 3 is a left side view thereof.

FIG. 4 is a front view thereof.

FIG. 5 is a rear view thereof

FIG. 6 is a top view thereof; and,

FIG. 7 is a bottom view thereof.

The broken line showing of the communication tool is included for the purpose of illustrating portions of the tool and forms no part of the claimed design.

1 Claim, 3 Drawing Sheets
